ATTORNEYS

UNITED STATES PATENT OFFICE.

BERTHA JANDORF BLOCK, OF BUFFALO, NEW YORK.

DESIGN FOR A BRACELET.

52,464.

Specification for Design.

Patented Sept. 24, 1918.

Application filed May 17, 1918. Serial No. 235,193. Term of patent 7 years.

To all whom it may concern:

Be it known that I, BERTHA JANDORF BLOCK, a citizen of the United States, residing at Buffalo, in the county of Erie and State of New York, have invented a new, original, and ornamental Design for Bracelets, of which the following is a specification.

The accompanying drawing is a perspective view of a bracelet embodying the design.

The bracelet shown comprises a watch A, a locket or the like B, and suitable connecting members or parts C secured at opposite ends to the watch and locket.

I claim:

The ornamental design for a bracelet as shown and described.

BERTHA JANDORF BLOCK.

Witnesses:

HOWARD D. ADAMS,
DAVID KAUFMAN.
